UNITED STATES PATENT OFFICE

2,260,555

LIQUID HYDROCARBON BURNER WITH
PILOT CHAMBERS

James L. Breese, Santa Fe, N. Mex., assignor to
Oil Devices, Santa Fe, N. Mex., a limited partnership of Illinois

Original application February 8, 1937, Serial No.
124,695. Divided and this application April 10,
1939, Serial No. 267,022

5 Claims. (Cl. 158—91)

My invention relates to an improvement in burners for burning liquid fuels, such as hydrocarbons, and has for one purpose the provision of a burner which can be turned down to a very small fire, or low draft, without destroying the characteristic mode of combustion described, for example, in my prior issued Patent No. 1,702,929, issued on February 19, 1929.

Another purpose is the provision of means for permitting low draft burning with such a burner, while preventing down drafts from upper portions of the combustion chamber, which would disadvantageously affect combustion.

Another purpose is the provision of such means which are adaptable for ready removal to permit easy cleaning of the burner and for adjustment of the burner capacity.

Another purpose is the provision of a burner for carrying on my characteristic combustion method which constitutes or includes a plurality of superposed burners of varying diameters.

Another purpose is the provision, in connection with one of my burners, of a lower supplementary burner which may have the functions of a pilot light for maintaining combustion during periods when a minimum heat or no heat is desired.

Other purposes will appear from time to time in the course of the specification and claims.

I illustrate my invention more or less diagrammatically in the accompanying drawing, which is a vertical axial section through a pot type liquid hydrocarbon burner involving my invention.

Like parts are indicated by like symbols throughout the specification and drawing.

The present application is a division of my co-pending application Serial No. 124,695 filed February 8, 1937.

Referring to the drawing, I generally indicate an outer furnace or heater shell and 2 an inner shell. 3 is a horizontal partition secured to the inner shell and provided with a central aperture 4. 5 is a preferably removable baffle, with a central aperture 6. 7 is a combustion chamber member, herein shown as generally cylindrical, with a bottom 8 which may be formed, if desired, in one piece and may be secured in any suitable way, as by bolts or welding 9, to the member 3.

10 is any suitable fuel supply pipe extending to the bottom 8. The means for supplying the fuel is not herein shown since it does not of itself form part of the present invention, but it will be understood that any suitable float chamber or the like may be employed for governing the desired flow of fuel, for example a liquid hydro-

carbon fuel, to the bottom 8. I illustrate as an example a manually controllable valve 10a.

11 is a closure member secured within the shell 2 and provided with apertures 12, which may be in a separate removable plate 13 closing the central aperture 14 of the member 11. I herein illustrate air inlet apertures 15 in the bottom of the shell 2 and it will be understood that any suitable means, whether by natural draft or forced draft, may be used to supply air to the space between the shells 1 and 2, which air is caused to flow through the apertures 15, upwardly through the apertures 12, and into the space between the members 1 and the shell 2. The member 1 is provided with an upper row of secondary air inlet apertures 16, herein shown as upwardly and inwardly inclined. A plurality of preferably smaller apertures 17 are shown arranged in rows in a lower portion of the member 1. The bottom row 18 is also indicated.

The member or pot wall 1 is provided with a lower portion 25 of smaller diameter, the two being connected by an offset or shelf 26 adapted to receive a removable baffle ring 27, with its central aperture 28. I thereby provide two separate chambers of different diameters, separated by a transverse partition 27, the interiors of the two chambers being put into communication with each other by the central aperture 28 of the baffle 27.

In the normal operation of the device, the characteristic combustion method of my Patent Number 1,702,929 may be carried on. The primary air supply enters through the apertures 17 and mingles with the hydrocarbon vaporized by combustion. The heat of combustion, once the device is in operation, vaporizes the hydrocarbon and the vaporized hydrocarbon rises and mixes with the primary air supply to form a primary mixture. This primary mixture moves upwardly toward and through the aperture 6 of the baffle 5 and there receives the secondary air supply admitted through the apertures 16. This produces a final mixture which burns and provides the heat for the stove or furnace unit.

Preferably, whether by natural draft or by any suitable fan or the like, not herein shown, sufficient air is admitted for maintaining combustion at a rate sufficient to give the desired heat. 50 Any suitable control means, thermostatic or otherwise, may be employed for controlling the desired heat produced.

In the event that it is desired to turn down the unit to a minimum heat, or to practically no heat, the fuel supply is reduced and combustion

is correspondingly reduced. In the structure as shown in my Patent Number 1,702,929, there is a limit below which the stove does not operate efficiently. For example, unless a sufficient air supply and sufficient rate of combustion is maintained, the secondary air or the air above the baffle 5 tends to eddy back and circulate down into the primary combustion zone, with the result that the balance between the primary and secondary zones is destroyed and my method of combustion is interrupted, resulting in carbon deposit, and inefficient combustion.

I find that the interposition of a baffle, such as the one shown herein at 27, prevents this down draft and my primary mixing and combustion may be carried on by means of the holes 18, and the secondary air may then be supplied by some or all of the holes 17. In other words, the primary zone moves down to or is limited to the holes below the baffle, and the holes above 20 the baffle, which previously operated as a source of primary air, then becomes the source of secondary air.

It will be realized that whereas I have described and illustrated a practical and operative device, nevertheless many changes may be made in the size, shape, number and disposition of parts without departing from the spirit of my invention. I therefore wish my description and drawing to be taken as in a broad sense illustrative or dia- 25 grammatic, rather than as limiting me to my precise showing.

For example, whereas I have described and shown the bottom 8 as generally flat, it will be understood that the terms are intended to be 30 employed with sufficient breadth to include a reasonable degree of concavity.

The use and operation of my invention are as follows:

I provide in effect two separate burners of different cubic content and of different diameter. When the device is running at high flame, the entire shell, including the portions 7 and 25, serves as a unitary chamber. Oil supplied along the line 10, the flow of which is controlled by any suitable valve such as 10a, is vaporized on the bottom 8 by the heat of combustion going on in the upper part of or above the chamber. The vaporized hydrocarbon, as it rises, mixes with the air from the primary inlets 17, 18, as above 40 described, and, when it receives the secondary air through the apertures 16, forms a final mixture and is burned. In this high stage of combustion, the baffle 27 could be removed without affecting the operation of the burner. However, when the valve 10a, or corresponding means, is employed to reduce the flow of liquid hydrocarbon to a minimum, then the apertures 17, above 45 the baffle, which at the high stage serve as primary air apertures, become secondary air apertures, and the first stage of hydroxylation takes place only in the smaller or pilot chamber defined by the bottom 8, the side wall 25 and the baffle 27. As the mixture flows upwardly through the aperture 28, it receives air from the apertures 17, which at the low stage corresponds to the secondary air supplied through the apertures 16 50 for the high stage.

It will be observed that but a single unitary oil supply is provided, namely, the line 10 and 70 its controlling valve, and the liquid hydrocarbon is vaporized on the bottom 8, regardless of whether the lower chamber or the entire chamber, including the upper portion, is being employed.

The aperture 28 is of sufficient cross sectional area to permit the combustion taking place above the baffle 27 at the high stages to vaporize the liquid hydrocarbon on the bottom 8. The parts are so proportioned that this vaporization may result at a sufficiently rapid rate to maintain adequate combustion at the high stage.

I claim:

1. In a mechanism for burning a liquid fuel, a main chamber and a supplemental chamber opening into the bottom thereof, the supplemental chamber being of smaller diameter than the main chamber, a unitary fuel supply means for both chambers, including a fuel delivery passage for admitting liquid fuel to the bottom of the supplemental chamber, the walls of both chambers being provided with a plurality of air inlet apertures, and a baffle interposed between the chambers, adjacent the junction of the two chambers, the baffle having an aperture of substantially smaller diameter than the diameter of the supplemental chamber, the supplemental chamber having a bottom of an area sufficient to serve as a vaporization surface for a supply of liquid fuel sufficient to maintain maximum combustion in or above the upper chamber.

2. In a mechanism for burning a liquid fuel, a main chamber and a supplemental chamber opening into the bottom thereof, the supplemental chamber being of smaller diameter than the main chamber, the two chambers being generally circular in cross section, and co-axial, a unitary fuel supply means for both chambers, including a fuel delivery passage adapted to direct liquid fuel to the bottom of the supplemental chamber, the walls of both chambers being provided with a plurality of primary air inlet apertures, a baffle interposed between the chambers, adjacent the junction of the two chambers, the baffle having a central aperture of substantially smaller diameter than the diameter of the supplemental chamber, the supplemental chamber having a bottom of an area sufficient to serve as a vaporization surface for a supply of liquid fuel sufficient to obtain maximum combustion in or above the main chamber, the cross sectional area of the aperture in the baffle being sufficient to admit the radiant heat of combustion necessary to vaporize sufficient fuel to maintain said maximum combustion.

3. In a mechanism for burning a liquid fuel, a main chamber and a supplemental chamber opening into the bottom thereof, the supplemental chamber being of smaller diameter than the main chamber, a unitary fuel supply means for both chambers, including a fuel delivery passage for admitting liquid fuel to the bottom of the supplemental chamber, the walls of both chambers being provided with a plurality of air inlet apertures, a baffle interposed between the chambers, adjacent the junction of the two chambers, the baffle having an aperture of substantially smaller diameter than the diameter of the supplemental chamber, the supplemental chamber having a bottom of an area sufficient to serve as a vaporization surface for a supply of liquid fuel sufficient to maintain maximum combustion in or above the upper chamber, and a centrally apertured baffle adjacent the top of the main chamber, said baffle partially closing the top of said main chamber.

4. In a mechanism for burning a liquid fuel, a main chamber and a supplemental chamber opening into the bottom thereof, the supplemental chamber being of smaller diameter than the

main chamber, a unitary fuel supply means for both chambers, including a fuel delivery passage for admitting liquid fuel to the bottom of the supplemental chamber, the walls of both chambers being provided with a plurality of air inlet apertures, a baffle interposed between the chambers, adjacent the junction of the two chambers, the baffle having an aperture of substantially smaller diameter than the diameter of the supplemental chamber, the supplemental chamber having a bottom of an area sufficient to serve as a vaporization surface for a supply of liquid fuel sufficient to maintain maximum combustion in or above the upper chamber, a centrally apertured baffle adjacent the top of the 15 main chamber, said baffle partially closing the top

of said main chamber, and means for supplying secondary air to the interior of the main chamber adjacent but below said last mentioned baffle.

5. An oil burning apparatus comprising a lower combustion chamber, means for admitting fuel to the lower chamber, a further chamber positioned above said lower chamber having a diameter substantially greater than said lower chamber, said chambers having a plurality of openings arranged peripherally therein for admitting air to said chambers, a third chamber positioned above said aforementioned chambers, the lower chambers having restricted openings at the top portions thereof.

JAMES L. BREESE.
